FOREIGN PATENT DOCUMENTS

CA 2136485 5/1996

Primary Examiner — Kelley Donnelly(74) *Attorney, Agent, or Firm* — Koppel, Patrick, Heybl & Philpott**CLAIM**

The ornamental design for a serving tray, as shown and described herein.

DESCRIPTION

FIG. 1 is a top, front, right side perspective view of a serving tray of the present invention;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.
